UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

PORTABLE UNIVERSAL DRILL MOUNTING

Application filed February 15, 1929. Serial No. 340,284.

This invention relates to rock drills, but more particularly to a portable mounting for rock drills.

One object of this invention is to provide a rigid mounting for rock drills which will stand firmly under the heavy vibrations set during the operation of drilling.

Another object is to provide a drill mounting which can be quickly and easily set up in a plurality of positions and which is adapted to permit the drilling of holes of any slant or inclination.

Another object is to construct a drill mounting which will permit of the ready transportation of the drill and mounting from place to place.

Other objects will be in part obvious and in part pointed out hereinafter.

All of these objects are obtained by the mechanism shown in the accompanying drawings, in which—

Figure 1 is a longitudinal front elevation of the mounting and the rock drill set up in a position to drill vertical holes;

Figure 2 is a side elevation of Figure 1;

Figure 3 is a sectional view of Figure 1 taken on the line 3—3 looking in the direction indicated by the arrows;

Figure 4 is a sectional view of Figure 2 taken on the line 4—4 looking in the direction indicated by the arrows;

Figure 5 is a side view of a winch adapted to be secured to the mounting for the purpose of moving the drill longitudinally of the mounting;

Figure 6 is a cross sectional view of Figure 5 taken on the line 6—6 looking in the direction indicated by the arrows;

Figure 7 is a detail view of one of the wheels of the mounting;

Figure 8 is a side view of the mounting and rock drill showing the position of the mounting when drilling holes close to the floor of a mine shaft or tunnel, and

Figure 9 is a view similar to Figure 8 showing the rock drill on the mounting advanced to its forwardmost position.

Referring more particularly to the drawings, a frame 10 is formed of two channel beams 12 and 14 secured together in parallel

positions. At the top the channel beams 12 and 14 are fastened to a yoke 16 by means of bolts 18. Wing pieces 20 on the yoke 16 support the shaft 22 on which is mounted a telescopic leg 24. The shaft 22 permits the leg 24 to be swung in any position in the plane perpendicular to the shaft 22. A rod 26 slides in the interior of the leg 24 and is secured in any desired position by means of a set screw 28 in a collar 30 on the leg 24.

At the bottom the channel beams are held together by a plate 32 bolted to angle irons 34 in any suitable manner. Gusset plates 36 and 38 riveted to the channel beams 12 and 14 respectively provide a mounting for sockets 40 and 42. These sockets are bolted to the gusset plates by bolts 44 and have apertures 46 and 48 through which legs 50 and 52 are passed when the mounting is in the position shown in Figure 1. The legs 50 and 52 are held securely in place by set screws 54 and 56 and are pointed at the ends to secure a firm footing on the rock floor 58. A second set of sockets 60 and 62 permit the legs 50 and 52 to be inserted when the mounting is set up in the position shown in Figures 8 and 9 and set screws 64 and 66 secure the legs firmly in this position.

A shaft 68 passing through the channel beams at a position near the top in Figure 1 provides a mounting for a pulley 70 and a shaft 72 at a point near the bottom of the channel beams mounted in the plate 32 forms an axle for a pulley 74.

Guides 76 and 78 secured to the channel beams in any suitable manner are adapted to receive the guideways (not shown) of a rock drill 80 of a standard make. The rock drill shell 82 is provided at its rearward end with a ring eye 84. The drill steel 86 is shown in position for drilling a hole 88 in the rock 58. A drill steel guide 90 is mounted at the lower end of the channel beams to steady the end of the drill steel 86. The guide 90 consists essentially of two yoke pieces 92 and 94 pivoted at 96 and 98 by means of shafts bolted to the channel beams at 100 and 102. The two yoke pieces 92 and 94 are locked together by a U-shaped bar 104 which passes through the yoke piece 94 and has its end burred or en-

larged as at 106 to prevent the accidental removal of the piece. The other end 108 passes over the yoke piece 92 as at 110 thus locking the two yoke pieces firmly together. When it is desired to remove the drill steel it is only necessary to draw up on the bar 104 and swing the yoke pieces apart on pivots 96 and 98.

In order to permit the drill to be withdrawn from the work a winch designated generally by 112 is secured to the channel beams by means of bolts 114 passing through a plate 116 which forms a base for the winch. Frame pieces 118 and 120 provide means for mounting the various parts of the winch. An axle 122 passes through the frame pieces 118 and 120 and wheels 124 and 126 are mounted on the axle. A gear 128 keyed to the axle 122 meshes with a gear 130 keyed to an axle 132 mounted in the frame pieces 118 and 120 at 184 and 136. A gear 138 keyed to the other end of the shaft 132 meshes with a gear 140 mounted on a shaft 142 which in turn is mounted in the frame pieces 118 and 120. A winch drum 144 is keyed to the shaft 142 by means of a key 146. To the opposite end of the drum a ratchet wheel 148 is secured by means of bolts 150. On a wing or extension 152 of the frame piece 120 a lever operated pawl 154 controlled by the handle 156 is mounted. A spring 158 secured to the lever arm 156 and the frame piece 120 is adapted to hold the pawl 154 in or out of operative position.

A brake drum 160 is rigidly mounted on the shaft 122 and a brake band 162 operated by a lever 164 controls the rotation of the shaft 122. The lever 164 is pivoted at 166.

Attached to one of the wheels in this instance 126 is a crank handle 168 by means of which the winch is operated by hand.

When the drill is in operation in the positions shown in Figures 1 and 2 it is necessary to have a means of hoisting the drill 80 and a means of prohibiting the too rapid downward movement of the drill, which rapid movement might injure the rotation mechanism (not shown) of the drill or other working parts. To this end a rope or cable 170 is secured to the ring eye 84 in the shell of the rock drill and this rope passes over the pulley 70 and downwardly to the winch drum 144. When it is desired to raise the drill the operator grasps the crank handle 168 and uses the wheel 126 as a crank to turn the shaft 122. Turning of the shaft 122 causes the gear 128 to revolve and this sets the gear train comprised of the gears 130, 138 and 140 in motion. Since the winch drum 144 is rigidly secured to the same shaft as the gear 140 the drum is revolved thus winding up the rope 170. The drum 144 is locked in place by the pawl 154 acting on the teeth of the ratchet ring 148. When it is desired to set the drill in operation again the pawl is raised by means of lever 156 and the weight of the rock drill

is sufficient to urge the drill steel 86 downward as the rock is cut away by the drill steel under the impact of the hammer piston (not shown). The amount of weight which the rock drill places on the drill steel 86 is controlled by the operator manipulating the lever 164 which tightens or loosens the brake band 162 on the brake drum 160.

The complete operation of the device is as follows: When it is desired to haul the mounting and rock drill to the work the wheels 124 and 126 are brought into contact with the ground by tilting the frame away from the horizontal position and the wheels then act as a carriage on which the mounting and the drill may be moved from place to place. The mounting may be set up from its traveling position to a vertical position as shown in Figures 1 and 2 by grasping the leg 24 and forcing the frame upward in much the same manner that a pike hole is used in raising a telegraph pole or flag staff.

In order to operate the drill in the position shown in Figures 8 and 9 the leg 172 is inserted in the hole 174 in the yoke 16. The leg 172 is secured in place by a set screw 176. The drill now occupies a position under the frame and a rope 178 is passed from the winch drum 144 over the pulley 70 to the pulley 72 as shown in dotted lines in Figure 8. From the pulley 72 the rope is brought back to the ring eye 84 in the shell of the rock drill. The drill may now be advanced toward the rock wall 180 for the purpose of drilling a hole in the position shown at 182. When the drill has advanced to the extreme position as shown in Figure 9 the rope 178 is removed and passes directly from the winch drum to the pulley 70 and is then hooked into the ring eye 84 on the rock drill shell. The drill may now be retracted by operating the crank handle 168.

When the wheels 124 and 126 are used for transporting the mechanism a spacer 121 is placed between a clutch member 123 and the hub 125. The wheel 126 and the spacer 121 are then free to rotate on the shaft 122 as shown in Figure 7. However when the wheel is to be used for operating the winch, the clutch member 123 is placed so as to engage notches 127 in the hub by means of the shoulder 129 formed on member 123. A pin 131 passing through clutch member 123 and the shaft 122 causes the shaft 122 to rotate with the wheel to operate the winch.

It will be seen from the foregoing description that this mounting permits the ready transportation of itself and the drill from place to place and that it is capable of being easily set up in a plurality of positions for drilling operations, and thus the objects hereinbefore mentioned are attained.

I claim:

1. A mounting for rock drills comprising a frame, a pair of legs secured to the frame at

one end thereof, a leg secured to the opposite end, sockets attached to the frame and adapted to secure the legs in a plurality of positions, a rock drill mounted on the frame, 5 an axle mounted on the frame, a pair of wheels mounted on the axle, a winch cooperating with the axle, a crank handle on one of the wheels, means adapted to operatively connect the wheel and the axle to transmit power applied to the crank handle from the axle to the winch, means for moving the rock drill toward and away from the rock being drilled, said means comprising a pair of pulleys and a rope cooperating with the 10 winch so that when the rope passes over both pulleys the rock drill is drawn toward the rock and when the rope passes over only the pulley farthest from the rock the drill is drawn from the rock when the winch is operated.

2. A mounting for rock drills, comprising a frame, a pair of adjustable legs, sockets adapted to hold said legs in a plurality of positions secured to the frame at one end 25 thereof, an adjustable leg secured to the opposite end of the frame, a rock drill slidably mounted on the frame, an axle mounted transversely on the frame, a pair of wheels mounted on the axle, a winch mounted on the frame and operably connected with the axle, a crank handle on one of the wheels, means adapted to transmit power applied to the crank handle from the axle to the winch, means for moving the rock drill toward and away from the rock being drilled, said means comprising a pair of pulleys and a rope cooperating with the winch so that when the rope passes over both pulleys the rock drill is drawn toward the rock and 30 when the rope passes over only the pulley farthest from the rock the drill is drawn from the rock when the winch is operated.

3. A mounting for rock drills, comprising a frame, a pair of adjustable legs, sockets 45 adapted to hold said legs in a plurality of positions secured to the frame at one end thereof, an adjustable telescopic leg secured to the opposite end of the frame, a rock drill slidably mounted on the frame, means for transporting the mounting comprising an axle mounted transversely on the frame, a pair of wheels mounted on the axle, a winch mounted on the frame and operably connected with the axle, a crank handle on one of the wheels, means adapted to transmit power applied to the crank handle from the axle to the winch, means for moving the rock drill toward and away from the rock being 50 drilled, said means comprising a pair of pulleys and a rope cooperating with the winch so that when the rope passes over both pulleys the rock drill is drawn toward the rock and when the rope passes over only the pulley farthest from the rock the drill is drawn 55

from the rock when the winch is operated.

In testimony whereof I have signed this specification.

CHARLES C. HANSEN.
